UNITED STATES PATENT OFFICE

2,414,536

SAND FEEDING MEANS

Royden C. Kirk, Arlington, Mass.

Application May 13, 1944, Serial No. 535,512

2 Claims. (Cl. 291—23)

1

This invention relates to improvements in sand feeding means particularly designed for feeding sand from a source of supply to a point of discharge in a sanding device for motor vehicles although the improvements may be used in sanding devices of other types or for feeding other granular material.

A sanding device of the general character to which the present improvements relate is disclosed in my Patent No. 2,212,865, granted August 27, 1940, for Improvements in sand device for automobiles. In this former patent, the sand supply receptacle is positioned immediately in the rear of a front wheel and normally concealed by the front fender. The sand is conveyed laterally beneath the running board to a point closely adjacent the rear fender at which point the sand is in position for gravitational discharge to be deposited on the ground immediately in front of the rear wheel.

One of the major problems in the commercial development of sanding devices for motor vehicles is that of means for controlling the delivery of the sand. Any of the usual forms of valve mechanisms may lead to trouble due to sticking of the valves or the mechanism for controlling the valves either due to the sand itself or due to freezing from moisture that may accumulate near the valve mechanism. In my prior patent, I disclosed a valveless construction by providing a motor driven conveyor belt for moving the sand from the receptacle to the delivery point. In such an arrangement, the sand is delivered only so long as the conveyor belt is in operation.

Another problem in the design of sanding devices for motor vehicles results from the fact that the sand supply receptacle, particularly when installed in the usual pleasure vehicle, cannot be placed at the most convenient point for deposit of the sand without destroying the appearance of the vehicle or impeding the movement of the doors. It is commercially desirable to conceal the sand supply receptacle and to place it at a point where there is sufficient space to maintain a substantially large supply of sand. This means that the sand cannot be gravitationally deposited from the receptacle and must be conveyed laterally to the point of discharge.

Furthermore, it is not easy to design simple mechanism which may be operated efficiently, no matter what position the vehicle may be in, with little expenditure of power to move the sand without danger of clogging or binding of the feeding means.

It is an object of the present invention to pro-

2

vide improved means for feeding sand or other granular materials which may be used in a sanding device for motor vehicles or other devices for feeding sand from a convenient source of supply to a point of discharge and which may be efficiently operated by a small amount of power for long periods of time under service conditions without requiring the attention of the operator.

It is more specifically an object of the present invention to provide a sand feeding device comprising a rotatable tubular member having an interior spiral fin whereby rotation of the tube will cause the sand to travel laterally towards the point of discharge.

It is further an object of the present invention to provide a sanding feeding device which may be manufactured from standard parts and can be readily adjusted to fit different sizes and types of motor vehicles in which the tubular means through which the sand is delivered laterally is telescopically constructed so that it may readily be shortened or lengthened as desired when installed in a motor vehicle.

Further objects and advantages of my improvements will be more readily apparent from the following description of a preferred embodiment thereof as disclosed in the accompanying drawings, in which:

Fig. 1 is a vertical, longitudinal section taken through the sanding device as installed in a motor vehicle, portions of the device being broken away for convenience in illustration;

Fig. 2 is a vertical section taken on the plane indicated 2—2 in Fig. 1 and showing the discharge nozzle;

Fig. 3 is a fragmentary vertical section taken through the mid portion of the tubular means through which the sand is delivered and illustrating the telescopic association of the parts;

Fig. 4 is a vertical section taken through the sand supply receptacle;

Fig. 5 is a side elevation of the sanding device as installed on a motor vehicle, the front fender being shown in section to expose the sand supply receptacle which is normally concealed by the front fender; and

Fig. 6 is a vertical section taken on the plane indicated 6—6 in Fig. 1 and illustrating the manner by which the sand is delivered into the sanding tube.

Referring to Fig. 5, there is illustrated a portion of motor vehicle 10 having a front wheel 12, rear wheel 14, a front fender 16, a rear fender 18, and a running board 20. The sanding device essentially comprises the sand supply receptacle

22, the casting 24 constituting the motor casing and the means for supporting the sand receptacle 22, the tubular means 26 through which the sand is conveyed laterally beneath the running board 20 and the splash guard 28 which protects the discharge opening through which the sand is delivered. The sanding device may conveniently be mounted on the motor vehicle such as by the brackets and straps 30. The sand supply receptacle as shown in Fig. 1 is provided with a tubular inlet 32 which extends through the top of the fender 16, the joint is made tight by the nut member 34 and the opening to the tube 32 may normally be closed by the cork 36 and cap 38. The casting 24 which carries the sand supply receptacle has a diagonal passageway 40 terminating in an elliptical opening 42 as shown in Fig. 6 on the rear face 44 of the casting.

The tubular means 26 essentially comprises a pair of outer telescopically associated tubes or cylindrical members 46 and 48 within which is enclosed an inner pair of telescopically associated tubular members 50 and 52. The tubular member 46 fits closely within the cylindrical flange 54 which extends from the casting 24, a weather-proof seal being provided by the packing 56. The inner tubular member 50 extends closely adjacent the face 44 of the casting 24 but is free to rotate with respect thereto. The joint is sealed to prevent the escape of sand by the gasket 58 held in place by the ring 60 welded or otherwise fixed near the end of the tube 50.

At its rear end, the tubular member 48 is closed by the screw cap 62 which may be removed to provide access to the bearing support for the rear end of the tube 52 which comprises the disc member 64 threaded into the tube 48 and supporting a bearing pin 66 which is fastened by the nut members 68. The rear end of the tube 52 is thus supported for rotation by a small bearing which may be adjusted to hold the tube 52 tightly but with freedom for rotation against the gasket 70 which provides a seal against entrance of the sand to the bearing. The small bearing permits rotation of the tubes 50 and 52 without excessive power. The inner pair of tubular members 50, 52 may be rotated by operation by a small size electric motor enclosed in the casing 72 and having a universal joint connection at 74 to the split drive pin 76, the ends 78 of which are spread apart and welded or otherwise connected to the forward end of the tube 50. Suitable gaskets 80 and 82 may be provided for sealing the bearing for the drive shaft 76. A nut 83 is provided to adjust the drive pin or shaft 76 and to hold the tube 50 in contact with the sealing gasket 58. The set screw 84 is provided as means to hold the pin or shaft 76 against rotation when desired as will be later described.

The sand is delivered through the passage 40 into the forward end of the tube 50 and conveyed laterally through the tube 50 into tube 52 to the delivery openings 86 as shown in Fig. 2 through which the sand passes to drop through the short discharge pipe 88, the point of discharge being protected by the splash guard 28. The movement of the sand through the tubes 50 and 52 is produced by the provision of spiral fin means within the tubes. In order to provide for the adjustment of the effective length of the distance between the sand supply receptacle and the point of discharge, a pair of spiral fins 90 and 92 are provided. The spiral fin 90 is welded or otherwise fixed at 94 near the forward end of the tube 50, and is also welded or otherwise fixed to the

rearward end of the tube 50 at 96 but it should be noted that the fin 90 freely extends beyond the tube 50. The other spiral fin 92 is welded or otherwise secured to the rearward end of the tube 52 at the point indicated 98 as shown in Fig. 2 while the forward end of the spiral fin 92 is welded at 100 to the forward end of the tube 52 as shown in Fig. 3. The free end of the fin 90 slides in beside the fin 92 and the two fins are held together with provision for relative rotatable movement by the clips 102. It will be apparent that by holding the tube 50 and rotating the tube 52 that the effective length may be increased or decreased. The tubes 50 and 52 are of the same diameter but a sliding joint is provided therebetween by an extension from the tube 50 comprising a tubular member 104 of slightly larger diameter, fixed to the tube 50 by the rivets 106. The tube 52 is free to slide with respect to the extension 104 of the tube 50, sealing means being provided if desired, such as the gaskets 108 and 110, the gasket 108 being fixed to the tube 52 while the gasket 110 is fixed to the extension 104.

It is believed to be new to feed sand or other granular material by a rotatable tube having an interior spiral fin fixed to the tube particularly in which the fin is fixed only at its ends to the tube. It should be understood that the sand will not fill the tube except that a pile will accumulate at the forward end as it is gravitally deposited from the supply receptacle. Rotation of the tube will feed the sand laterally and allow more sand to fall from the source of supply. The same will be fed laterally along the bottom of the tube by the spiral fin. When the sand reaches the rear end of the tube 52 it will be gravitally discharged but the sand will not be discharged except during rotation of the feeding tube even though the vehicle may be on a hill with the feeding tube in an inclined position.

When a sanding device of the type disclosed is installed on a motor vehicle as shown in Fig. 5, it is often desirable to adjust the length of the conveyor or feeding means between the supply inlet and discharge outlet to fit different sizes and types of vehicles. If the spiral feeding tube is in one piece, the device would have to be made in different sizes. In my improved construction, the outer casing and inner feeding tube are made in relatively slidably sections to provide for the necessary adjustment in length. The front end of the device is fixed in position by mounting the supply receptacle. The tube 50 is then locked by tightening the set screw 84. After removing the cap 62, the tube 52 is then turned from its rear end by means of the nut 68 and the relative movement of the spiral fins will produce a longitudinal displacement to shorten or lengthen the sand feeding means. After adjustment, the cap 62 is replaced, the rear end of the device is fixed in position and the set screw 84 is released. The device is then ready to be operated.

I claim:

1. In a device for feeding sand, a sectional feeding tube, the sections of said tube being telescopically associated, a spiral fin fixed to each of said sections, one of said fins being free at one end to screw into the other spiral fin, means for rotatably mounting the opposite ends of the feeding tube to hold the sections against relative axial movement and means for rotating said tube from one end thereof whereby rotatable movement is transmitted between the sections through the cooperation of the spiral fins.

2. In a sanding device for motor vehicles, a

casing, means for mounting the casing at its opposite ends on a motor vehicle, a sand supply receptacle mounted on said casing at its feeding end, gravital valveless sand discharge means at the opposite end of the casing, said casing having telescopically associated sections for adjusting the length of the casing between the feeding and discharge ends and rotatable tubular spiral conveyor means for feeding the sand through said

casing from the feeding end to the discharge end, said spiral conveyor means comprising telescoped and interthreaded sections mounted for rotation at the feeding and discharge ends of the casing respectively, whereby the length of the spiral conveyor means may be adjusted by rotating one section with respect to the other section.

ROYDEN C. KIRK.
